FIG. 3.

FIG. 4.

ATTORNEY

UNITED STATES PATENT OFFICE.

ANNIE M. CAUSEY, OF MALVERN, ARKANSAS.

DRAFT-REGULATOR.

1,290,714.

Specification of Letters Patent.

Patented Jan. 7, 1919.

Application filed July 2, 1917. Serial No. 178,292.

To all whom it may concern:

Be it known that I, ANNIE M. CAUSEY, a citizen of the United States, residing at Malvern, in the county of Hot Springs and State 5 of Arkansas, have invented certain new and useful Improvements in Draft-Regulators, of which the following is a specification.

This invention relates to new and useful improvements in stoves and the principal object of the invention is to provide means for automatically regulating the temperature of the oven of the stove.

Another object of the invention is to provide means for adjusting the regulating 15 means whereby the same may be set to operate at any desired temperature.

Another object of the invention is to so form the device that the same may be attached to the oven door without changing 20 the formation of the same but little.

Another object of the invention is to provide indicating means showing at what degree of temperature the regulating means will operate.

Another object of the invention is to provide a device of this character which is simple and durable in construction, reliable and efficient in operation and one which can be manufactured and placed upon the 25 market at a minimum cost.

The invention also consists in certain other features of construction and in the combination and arrangement of the several parts, to be hereinafter fully described, illustrated 30 in the accompanying drawings and specifically pointed out in the appended claims.

In describing my invention in detail, reference will be had to the accompanying drawings, wherein like characters denote like 40 or corresponding parts throughout the several views, and in which:

Figure 1 is a front view of an oven door to which the invention is applied.

Fig. 2 is a section on line 2—2 of Fig. 1.

Fig. 3 is a rear view of part of the invention.

Fig. 4 is a section on line 4—4 of Fig. 3.

In these figures, 1 represents an oven door provided with upper and lower ventilating 50 openings 2 and 3 and these openings are regulated by the dampers 4 and 5, each of these dampers being secured on the square end of a member 6 mounted to turn in a bearing 7 located within the ventilating 55 openings before described. Each member is

provided with a flange 7' and a right angularly extending part 8. The parts 8 of the members are connected by a rod 9. This rod 9 carries a sleeve 10, adjustably mounted thereon by means of a thumb nut 11. 12 is a 60 rod having a forked end 13 which engages the rod 9 below the sleeve 10 and the other end of this rod has a V-shaped end 14 which engages with a V-shaped depression in a stem 15 having a part bent at right angles 65 and passing through the oven door and having a hand 16 secured thereon, said hand being mounted above a dial 17, located on the outer side of the oven door. Collars 15' and 15" keep the stem in position. 70

I locate on the inner side of the door a pair of bars 18 and 18' made of expansive metal and having their outer ends secured to the door as at 19 and their inner ends forked and pivoted to the bar 12. These 75 bars extend at right angles to the rod 12 and are located one above the said rod and the other below the same. The strap 19' secured to the door embraces the bar 18' adjacent its inner end. It will be seen that the pivotal points of these bars are located close together on the rod 12 so that a maximum amount of movement of said rod 12 is secured by a minimum amount of movement of said bars, and the closer together these pivotal points are the greater will be the movement of said rod 12, so that the movement of said rod 12 may be adjusted by the position 80 of said bars in relation to each other. 85

The stem 15 and the rod 12 are in line under normal conditions, but as the heat of the oven increases the thermal members 18 and 18' expand and impart a pivotal movement to the bar 12 to lift its forked end 13 and depress its pointed end 14 and the notched end 90 of the stem 15, whereby the hand 16 is caused to travel over the dial 17 to indicate the temperature of the oven. As the oven cools the parts 12 and 15 return to normal position by reason of the interengaging projection 14 and the coöperating notch in the end 95 of the stem 15.

When the heat in the oven reaches a certain temperature, the bars 18 and 18' will expand, thus raising the outer end of bar 12 105 and, by means of the sleeve 10 and the rod 9, opening the dampers to cool off the oven. If the oven should cool too much, the bars will contract, so as to lower the bar 12 and thus close the dampers, so that the action is 110

automatic. The point of closing of the dampers may be regulated by adjusting the collar 10 on the rod 9.

It will be seen that the movement of the 5 rod 12 will cause the hand 16 to move over the dial so as to register such movement thereon. The amount of such movement may be regulated by the length of the stem 15 as the shorter this stem is the greater 10 will be the travel of the hand 16.

This invention will automatically regulate the temperature of the oven, without the attention of the cook, thus avoiding excessive heating and burning of the food, regardless 15 of the amount of fire in the stove.

It is thought from the foregoing that the advantages and novel features of my invention will be readily apparent.

I desire it to be understood that I may 20 make slight changes in the construction and in the combination and arrangement of the several parts, provided that such changes fall within the scope of the appended claims.

I claim as my invention:

25 1. Means for regulating the heat of an oven, the same comprising a damper, indicating means embodying a dial and a hand,

a stem carrying the hand and having a portion bent about at a right angle, a rod in line with the bent end of the stem and having a 30 loose joint connection therewith at one end, an expansion bar connected with the rod at a point between its ends, and a rod connected with the damper and having connection with the before mentioned rod, all disposed to operate substantially in the manner set forth. 35

2. A stove comprising an oven, dampers located on the door thereof, a rod connecting the dampers, a sleeve adjustably mounted on said rod, a bar having one end engaging with 40 said rod below the sleeve, a stem pivoted in the door and connected with the other end of said bar, a hand connected to said stem, a dial on the door below the hand and bars of expansive metal each having one end connected to the door and the other end pivoted to said bar. 45

In testimony whereof I affix my signature in presence of two witnesses.

ANNIE M. CAUSEY.
